PAGE 2

FIG. 3

FIG. 4

FIG. 5

FIG. 6

FIG. 1 is a top plan view of a post lamp showing my new design;

FIG. 2 is a side elevation thereof as shown in FIG. 1, with the post shown broken away in part to indicate indeterminate length;

FIG. 3 is a top plan view of a modified form of the post lamp shown in FIG. 1;

FIG. 4 is a side elevation thereof as shown in FIG. 3, with the post fragmentarily shown for convenience of illustration only;

FIG. 5 is a top plan view of a further modified form of the post lamp shown in FIG. 1; and

FIG. 6 is a side elevation thereof as shown in FIG. 5 with the post fragmentarily shown for convenience of illustration only.

The dominant features of my new design reside in those portions shown by means of full lines in the drawing.

The opposite side view of the post lamp in FIGS. 2, 4 and 6 are the same as shown.

I claim:

The ornamental design for a post lamp, substantially as shown and described.
